J. T. AUSTIN

REINFORCED CABLE

Filed Sept. 29, 1922

FIG. 1.

FIG. 2.

FIG. 3.

INVENTOR

J. T. Austin
H. H. Hutchinson

ATTORNEY.

UNITED STATES PATENT OFFICE.

JOHN T. AUSTIN, OF HARTFORD, CONNECTICUT.

REENFORCED CABLE.

Application filed September 29, 1922. Serial No. 591,309.

To all whom it may concern:

Be it known that JOHN T. AUSTIN, citizen of the United States, residing at Hartford, in the county of Hartford and 5 State of Connecticut, has invented certain new and useful Improvements in Reenforced Cables, of which the following is a specification.

This invention relates to a reenforced cable. I use the term cable in a general sense with the object primarily of including such an article when made of steel but also equivalent things as hemp, rope, textile rope, and things of like nature. When 10 such a steel cable or its equivalent is cut, it usually uncoils or unwraps at the place of cutting, this being particularly true of cable or a metal structure made up of strands. The primary object of the invention 15 is the provision of means by which the cable or analogous article can be effectually prevented from unwrapping or unravelling from the place where the cut is made.

In the drawing accompanying and forming part of the present specification, I have shown in detail a form of embodiment of the invention which so that those skilled in the art can practice the invention, will be set forth fully in the following description. I am not restricted, however, to this disclosure. I may depart therefrom in a 20 number of respects within the scope of the invention defined by the claim following said description.

35 Referring to the drawing:

Fig. 1 is a side elevation of a reenforced cable involving the invention.

Fig. 2 is a cross section on the line 2—2 of Fig. 1 looking toward the right.

40 Fig. 3 is an elevation of the cable in loop form.

Like characters refer to like parts throughout the several views.

In the drawing the numeral 2 denotes a 45 length of steel cable which can be made of twisted lengths of wire. As I have already observed, the term "cable" is used in a

broad sense to include for instance not only these twisted wires, but strands of hemp, or textile material, and things of a like 50 nature.

When such a cable or equivalent or loop is cut, it is more than apt to become un-twisted commencing at the cut and I provide a structure by which such unravelling 55 or uncoiling is not possible. I apply to the cable 2 a tube 3 which may be metal or something of an analogous character and which acts effectively to prevent the cable 2 from unravelling.

When such an article unravels many disagreeable effects are present, this being especially the case with metal or wire cable, which is quite apt to scratch or injure the hands or some other part of the body. 60 The tube 3 of metal will prevent this bad condition. The reenforced cable at its reenforced end can be formed into a strong loop 65 4, the free portion of the reenforced loop being wrapped around the reenforced part of 70 the cable 2, the tube 3 being sufficiently flexible as to permit this condition.

The device comprises a core having a reenforced portion or wrapping free of the same, but tightly enveloping the core so 75 that where the core is cut the core and the wrapping thereabout can be formed into a loop.

What I claim is:

A looped structure comprising a wire 80 cable, a short metal retaining tube surrounding the cable only adjacent an end thereof, the cable and tube being bent into the form of a loop with the end of the cable surrounded by an end of the tube 85 wrapped around the other end of the tube, said tube having sufficient rigidity to retain the cable in looped formation.

In testimony whereof I hereby affix my signature.

JOHN T. AUSTIN.
